CLAIM

The ornamental design for a container with primary and secondary storage, as shown and described.

DESCRIPTION

FIG. 1 is a top, front perspective view of a container with primary and secondary storage, showing the new design; FIG. 2 is a top, back perspective view of the container with primary and secondary storage;

FIG. 3 is a bottom, front perspective view of the container with primary and secondary storage;

FIG. 4 is a bottom, back perspective view of the container with primary and secondary storage;

FIG. 5 is a bottom, right-side perspective view of the container with primary and secondary storage;

FIG. 6 is a front view of the container with primary and secondary storage;

FIG. 7 is a back view of the container with primary and secondary storage;

FIG. 8 is a right-side view of the container with primary and secondary storage;

FIG. 9 is a left-side view of the container with primary and secondary storage;

FIG. 10 is a top view of the container with primary and secondary storage;

FIG. 11 is a bottom view of the container with primary and secondary storage;

FIG. 12 is a top, front perspective view of a base of the container with primary and secondary storage;

FIG. 13 is a top, back perspective view of the base of the container with primary and secondary storage;

FIG. 14 is a top, right-side perspective view of the base of the container with primary and secondary storage;

FIG. 15 is top, left-side perspective view of the base of the container with primary and secondary storage;

FIG. 16 is bottom, front perspective view of the base of the container with primary and secondary storage;

FIG. 17 is a bottom, back perspective view of the base of the container with primary and secondary storage;

FIG. 18 is a bottom, right-side perspective view of the base of the container with primary and secondary storage;

FIG. 19 is a front perspective view of the base of the container with primary and secondary storage;

FIG. 20 is a back perspective view of the base of the container with primary and secondary storage;

FIG. 21 is a right-side perspective view of the base of the container with primary and secondary storage;

FIG. 22 is a left-side perspective view of the base of the container with primary and secondary storage;

FIG. 23 is a top perspective view of the base of the container with primary and secondary storage;

FIG. 24 is a bottom perspective view of the base of the container with primary and secondary storage;

FIG. 25 is a top, front perspective view of a lid of the container with primary and secondary storage;

FIG. 26 is a top, back perspective view of the lid of the container with primary and secondary storage;

FIG. 27 is a bottom, front perspective view of the lid of the container with primary and secondary storage;

FIG. 28 is a bottom, back perspective view of the lid of the container with primary and secondary storage;

FIG. 29 is a bottom, right-side perspective view of the lid of the container with primary and secondary storage;

FIG. 30 is a front view of the lid of the container with primary and secondary storage;

FIG. 31 is a back view of the lid of the container with primary and secondary storage;

FIG. 32 is a right-side view of the lid of the container with primary and secondary storage;

FIG. 33 is a left-side view of the lid of the container with primary and secondary storage;

FIG. 34 is a top view of the lid of the container with primary and secondary storage;

FIG. 35 is a bottom view of the lid of the container with primary and secondary storage;

FIG. 36 is a top, front perspective view of an insert of the lid of the container with primary and secondary storage;

FIG. 37 is a top, back perspective view of the insert of the lid of the container with primary and secondary storage;

FIG. 38 is a bottom, front perspective view of the insert of the lid of the container with primary and secondary storage;

FIG. 39 is a bottom, back perspective view of the insert of the lid of the container with primary and secondary storage;

FIG. 40 is a front view of the insert of the lid of the container with primary and secondary storage;

FIG. 41 is a back view of the insert of the lid of the container with primary and secondary storage;

FIG. 42 is a right-side view of the insert of the lid of the container with primary and secondary storage;

FIG. 43 is a left-side view of the insert of the lid of the container with primary and secondary storage;

FIG. 44 is a top view of the insert of the lid of the container with primary and secondary storage;

FIG. 45 is a bottom view of the insert of the lid of the container with primary and secondary storage;

FIG. 46 is a top, front perspective view of a lower portion of the lid of the container with primary and secondary storage;

FIG. 47 is a top, back perspective view of the lower portion of the lid of the container with primary and secondary storage;

FIG. 48 is a bottom, front perspective view of the lower portion of the lid of the container with primary and secondary storage;

FIG. 49 is a bottom, back perspective view of the lower portion of the lid of the container with primary and secondary storage;

FIG. 50 is a front view of the lower portion of the lid of the container with primary and secondary storage;

FIG. 51 is a back view of the lower portion of the lid of the container with primary and secondary storage;

FIG. 52 is a right-side view of the lower portion of the lid of the container with primary and secondary storage;

FIG. 53 is a left-side view of the lower portion of the lid of the container with primary and secondary storage;

FIG. 54 is a top view of the lower portion of the lid of the container with primary and secondary storage; and,

FIG. 55 is a bottom view of the lower portion of the lid of the container with primary and secondary storage.
